Primary Examiner — Catherine R Oliver-Garcia(57) **CLAIM**

The ornamental design for an openable fishing lure container, as shown and described.

DESCRIPTION

FIG. 1 is a front perspective view of a fishing lure container having a cap which can move between a closed position and an open position, wherein the cap is in the closed position; FIG. 2 is a front elevational view thereof; FIG. 3 is a rear elevational view thereof; FIG. 4 is a right side elevational view thereof; FIG. 5 is a left side elevational view thereof; FIG. 6 is a top plan view thereof; FIG. 7 is a bottom plan view thereof; FIG. 8 is a rear perspective view thereof; FIG. 9 is a front perspective view of the fishing lure container, wherein the cap is in the open position; FIG. 10 is a front elevational view thereof; FIG. 11 is a rear elevational view thereof; FIG. 12 is a right side elevational view thereof; FIG. 13 is a left side elevational view thereof; FIG. 14 is a top plan view thereof; FIG. 15 is a bottom plan view thereof; and, FIG. 16 is a rear perspective view thereof.

The broken lines in the drawings illustrate portions of the openable fishing lure container that form no part of the claimed design.

1 Claim, 15 Drawing Sheets(56)
